UNITED STATES PATENT OFFICE

LUTHER J. KIGER, OF NASHVILLE, TENNESSEE, ASSIGNOR TO NATIONAL AUTO TAG SEAL CORPORATION, OF NASHVILLE, TENNESSEE, A CORPORATION OF TENNESSEE

IDENTIFICATION TAG CASE MOUNTING

Application filed February 20, 1930. Serial No. 430,030.

This invention relates to identification tag case mountings, and an object of the invention is to provide for mounting the identification tag in close proximity with the license plate, so that the same will be permanently attached to the automobile.

Further objects of the invention are to provide a mounting of the character referred to that is strong, compact and durable, thoroughly reliable for its intended purpose, very simple in its method of assembly, and comparatively inexpensive to manufacture and install.

With the foregoing and other objects in view, the invention consists of a novel construction, combination and arrangement of parts, as will be hereinafter more specifically described and illustrated in the accompanying drawings, wherein is disclosed an embodiment of the invention, but it is to be understood that changes, variations, and modifications, may be resorted to without departing from the spirit of the claims hereto appended.

In the drawings, wherein like reference characters denote corresponding parts throughout the several views:

Figure 1 is a front elevation of a license tag showing the mounting of the present invention applied thereto.

Fig. 2 is a detailed vertical section taken substantially on the line 2-2 of Fig. 1, and showing the identification tag casing folded behind the license plate, certain of the elements including the casing, being shown in side elevation.

Fig. 3 is a detailed longitudinal section through the supporting bolt, and

Fig. 4 is a transverse section taken substantially on the line 4-4 of Fig. 3.

This invention is clearly adapted for supporting identification tag casings shown in application, Serial No. 430,029, filed this 20th day of February, 1930.

Referring to the drawings in detail, 5 indicates a rectangular, metallic license plate having numerals thereon to identify the automobile to which the license tag is attached. It is to be understood that a conventional license tag is provided with a pair of elongated slots 6 in the upper margin thereof, or

may be provided with an opening 7 in each of the four corners thereof.

Extending from the rear of an automobile, not shown in the drawings, are the customary pair of supporting arms 8, 9 which have a portion thereof disposed in horizontal alignment with each other. The upper end of each arm is formed with an opening 10 to receive the supporting bolt indicated generally at 11. This supporting bolt 11 includes a semi-spherical head 12 on one end extending inwardly from which is a shank 13. The head 12 is provided with a transverse groove 15 to receive the end of a screw driver for turning the bolt.

A shank 13 is threaded the major portion of its length as at 14, and this threaded portion merges at its inner end with a reduced beveled stem 16 that in turn merges with a bullet-shaped head 17 on the inner end of the shank.

A cap 18 is adapted to be disposed over a portion of the threaded portion 14 of the shank and the head 17. The cap 18 is hollow and cylindrical. One end of the cap 18 is closed by an end wall 19, while the other end thereof is open. About the open end, there is an annular inwardly projecting shoulder 20 that bears against one end of the sleeve 21 and holds the same within the cap.

The side wall of the tubular sleeve 21 is slotted in a U-shape and bent inwardly to form a tongue 22. This tongue 22 projects into the interior of the cap in the path of the head 17.

It will be understood that it is only necessary to use one mounting on one supporting arm, because it is only necessary to mount one license tag casing for each license plate.

In assembling the mounting, the head 12 is disposed in abutting relation to the inner face of one supporting arm, although the mounting may be applied to either arm 8 or 9. The threaded portion 14 of the shank is extended through the opening 10 in the arm and projects outwardly therefrom. A nut 23 is threaded on the bolt 11 and bears against the outer side of the license plate 5.

A helical coil spring 24 is mounted on the threaded portion 14 of the bolt, said spring having one end bearing against the outer face of arm 9, and the other end thereof bearing 5 against the identification tag casing indicated generally at 25.

This identification tag casing 25 is more particularly described in my application Serial No. 430,029, filed this 20th day of February, 1930.

This identification tag casing 25 for the purpose of the present invention, may be described as an elongated rectangular body having an opening 26 adjacent its upper end 15 through which the threaded portion 14 of the bolt extends.

It is to be understood that the identification tag casing 25 is free to rotate on the threaded portion 14 of the bolt, but is normally held from rotating thereon by the tension of the coil spring 24. The outer face of the casing 25 bears against the inner face of the license plate 5, which license plate is mounted on the threaded portion 14 of the bolt 11.

The inner end of the cap 18, bears against the nut 23 and prevents removal of said nut. It will be understood that the shank 13 of the bolt may be inserted thru either the slot 30 6 or one of the openings 7 depending upon the spaced relation of the supporting arms 8 and 9. The last operation in the assembly of the mounting, is to slip the cap 18 over the outer end of shank 13. The tongue 22 35 flexes over the bullet head 17 and locks against the head 17 so that the bolt cannot be removed from the arm 9 and the identification tag casing 25 cannot be removed from the mounting without cutting the parts.

40 In normal position, the casing 25 is folded behind the license tag plate as shown in Fig. 2 of the drawings. In event the registration and identification of the automobile are questioned, the casing 25 may be, rotated upwardly on the bolt 11 as shown in Fig. 1 of the drawings, whereby the information contained on the tag may be readily seen to satisfy inquiry.

It is to be understood that by describing in 50 detail herein any particular form, structure, or arrangement, it is not intended to limit the invention beyond the terms of the several claims, or the requirements of the prior art.

Having thus described my invention, what 55 I claim as new is:—

1. In combination, a supporting arm adapted for attachment to an automobile having an opening in its upper end, an identification tag casing having an opening in one end, a license tag plate having openings therein, a supporting bolt including a shank having a portion thereof threaded, heads on the opposite ends of the bolt, said shank extending through said openings in the arm and casing, and one of said openings in the tag plate, a

spring supported on said threaded portion of the bolt between said arm and casing, and a lockable cap disposed over one head of the bolt.

2. In combination, a supporting arm adapted for attachment to an automobile having an opening in its upper end, an identification tag casing having an opening in one end, a license tag plate having openings therein, a supporting bolt including a shank having a portion thereof threaded, heads on the opposite ends of the bolt, said shank extending through said openings in the arm and casing, and one of said openings in the tag plate, a spring supported on said threaded portion of the bolt between said arm and casing, a lockable cap disposed over one head of the bolt, a sleeve in the cap, an inwardly directed flange on one end of the cap bearing against one end of the sleeve, and a flexible tongue 80 on the sleeve for locking against said one head of the bolt.

3. In combination, a supporting arm adapted for attachment to an automobile having an opening in its upper end, an identification tag casing having an opening in one end, a license tag plate having openings therein, a supporting bolt including a shank having a portion thereof threaded, heads on the opposite ends of the bolt, said shank extending through 90 said openings in the arm and the casing, and one of said openings in the tag plate, a spring supported on said threaded portion of the bolt between said arm and casing, a lockable cap disposed over one head of the bolt, a sleeve in the cap, an inwardly directed flange on one end of the cap bearing against one end of the sleeve, and a flexible tongue 85 on the sleeve for locking against said one head of the bolt.

4. In combination, a supporting arm adapted for attachment to an automobile having an opening in its upper end, an identification tag casing having an opening in one end, a license tag plate having openings therein, a supporting bolt including a shank having a portion thereof threaded, heads on the opposite ends of the bolt, said shank extending through 100 said openings in the arm and the casing, and one of said openings in the tag plate, a spring supported on said threaded portion of the bolt between said arm and casing, a lockable cap disposed over one head of the bolt, a sleeve in the cap, an inwardly directed flange on one end of the cap bearing against one end of the sleeve, a flexible tongue on the sleeve for locking against said one head of the bolt, said one head being bullet-shaped.

4. In combination, a supporting arm adapted for attachment to an automobile having an opening in its upper end, an identification tag casing having an opening in one end, a license tag plate having openings therein, a supporting bolt including a shank having a portion thereof threaded, heads on the opposite ends of the bolt, said shank extending through 110 said openings in the arm and the casing and one of said openings in the tag plate, a spring supported on said threaded portion of the bolt between said arm and casing, a lockable cap disposed over one head of the bolt, a sleeve in the cap, an inwardly directed flange on one end of the cap bearing against one end of the sleeve, a flexible tongue on the sleeve for locking against said one head of the bolt, said one head being bullet-shaped, and said spring bearing against the casing on one end and on the arm at the other end.

In testimony whereof I affix my signature.
LUTHER J. KIGER.
